UNITED STATES PATENT OFFICE.

JOHN J. HVEEM, OF CHICAGO, ILLINOIS, ASSIGNOR TO WILLIAM H. MINER, OF CHAZY,
NEW YORK.

SIDE BEARING FOR RAILWAY-CARS.

1,290,207.

Specification of Letters Patent.

Patented Jan. 7, 1919.

Application filed May 21, 1917. Serial No. 169,892.

To all whom it may concern:

Be it known that I, JOHN J. HVEEM, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

This invention relates to improvements in side bearings for railway cars.

One object of the invention is to provide a simple railway side bearing more particularly adapted for use on railway cars and comprised of few parts easily and cheaply manufactured and assembled.

Another object of the invention is to provide a side bearing of the character described and which comprises a base casting, an anti-friction roller, and unitary means for both guiding the roller and also for preventing the roller from becoming disengaged from the base casting.

In the drawing forming a part of this specification, Figure 1 is a part side elevation, part vertical section of a side bearing embodying my improvements shown in position between a body and truck bolster of a car. Fig. 2 is an end elevational view, looking from the right, of the structure shown in Fig. 1. Fig. 3 is a vertical sectional view, taken substantially on the line 3-3 of Fig. 1. And Fig. 4 is a horizontal detailed sectional view, taken on the line 4-4 of Fig. 1.

In said drawing, 10 denotes a portion of a body bolster of a car and 11 a portion of a truck bolster, the improved roller side bearing, designated generally by the reference A, being interposed between the bolsters and secured to the truck bolster.

The improved bearing A, as shown, comprises a base casting 12 having outstanding flanges 13 by which it is riveted to the truck bolster, a pair of up-standing side walls 14-14 and one end wall 15. The bottom wall of the base casting 12 forms a bearing surface 16 for the anti-friction roller 17 which rolls back and forth thereon, as will be understood.

In order to maintain the anti-friction roller in proper position, and guide the same in its back and forth movements, I have pro-

vided a rectangular guiding frame, designated generally by the reference B. Said frame B, as shown, comprises a pair of side flanges 18-18 which are longitudinally recessed on their inner faces, as indicated at 19, to receive the out-turned flanges 20 of the side walls 14 of the base casting. With this arrangement, it is obvious that the frame B is slidable horizontally with respect to the base casting but is prevented from vertical movement with respect thereto. Said frame B is of substantially rectangular form and encircles the roller 17. On either side of the roller, said frame B is provided with upwardly extending fingers 21-21 which are curved toward each other so as to correspond to the cylindrical surface of the anti-friction roller. As clearly appears from Fig. 1, said curved fingers 21 extend above a horizontal plane passing through the axis of the roller 17 and consequently the anti-friction roller 17 is prevented from becoming displaced vertically from the base casting. It is also evident that the anti-friction roller and the frame B will move in unison as the roller moves back and forth.

In order to maintain the roller in normal position after each actuation, the frame B is provided with an extension 22 from one end thereof which passes through a spring 23 formed on the adjacent end of the base casting 12. Said housing 23 has mounted therewithin a coil spring 24 which fits over the reduced end 25 of said extension 22, said spring 24 being engaged at its 90 ends with followers 26 and 27. A nut 28 is carried by the outer end of the reduced extension 25 so that the outer follower 27 moves inwardly upon inward movement of the nut 28, thus compressing the spring 24 95 against the follower 26. Similarly, upon movement of the extension 22 to the right, as viewed in Fig. 1, the follower 26 will be engaged by the shoulder 29 and the spring 24 compressed against the other follower 27. 100 Consequently, as the roller 17 is moved to either side of normal, the spring 24 will be compressed and upon release of pressure on the roller, the spring will expand and force the frame B and the roller 17 to normal 105 position.

After the base casting is secured in position, the frame B is first assembled with the anti-friction roller and the frame B and roller are slid horizontally of the base cast- 110

ing from the left-hand end thereof, as viewed in Fig. 1, so as to engage the frame B with the flanges 20. The spring 24 and followers 26 and 27 are placed within the 5 housing 23 before the reduced extension 25 is passed through the followers, as will be understood. The nut 28 is applied finally and when all the parts are thus assembled, accidental removal of the roller or any other 10 part of the side bearing is prevented.

I claim:

1. In a side bearing, the combination with a retaining casting, of an antifriction roller mounted within said casting and bodily 15 movable with respect thereto, of a guiding frame slidably mounted with respect to said casting, said guiding frame having portions thereof curved to correspond with the curvature of the bearing surface of the 20 roller and partly overlapping the latter to thereby prevent the roller from becoming displaced, and means for automatically returning said guiding frame to normal after 25 each actuation of the roller.
2. In a side bearing for railway cars and

the like, the combination with a retaining casting having parallel side walls, of a roller adapted to roll between said side walls, a frame slidably mounted on said retaining casting and having curved portions overlapping the bearing surface of the roller above the axis thereof and adapted to prevent the roller from separating from the retaining casting, and means for centering 30 said frame and roller.

3. In a roller side bearing, the combination with a base casting having up-standing side walls, of a roller adapted to roll on said base casting between said walls, a guiding frame slidably mounted on said base casting and having arms extending partly over the periphery of said roller on opposite sides of its axis, and spring means for automatically centering said frame and roller after 40 each actuation of the side bearing.

In witness that I claim the foregoing I have hereunto subscribed my name this 30th day of April, 1917.

JOHN J. HVEEM.
